UNITED STATES PATENT OFFICE

JAMES K. MATTER AND CARLTON G. TOWNE, OF NEW KENSINGTON, PENNSYLVANIA,
ASSIGNORS TO THE ALUMINUM COOKING UTENSIL COMPANY, OF NEW KENSINGTON,
PENNSYLVANIA, A CORPORATION OF PENNSYLVANIA

DESIGN FOR A COFFEEPOT

Application filed May 31, 1932. Serial No. 43,949. Term of patent 7 years.

To all whom it may concern:

Be it known that we, JAMES K. MATTER and CARLTON G. TOWNE, citizens of the United States, residing at New Kensington, in the county of Westmoreland and State of Pennsylvania, have invented a new, original, and ornamental Design for a Coffee Pot, of which the following is a specification, reference being had to the accompanying drawing, forming a part thereof.

Fig. 1 is a perspective view of a coffee pot showing our new design; and Fig. 2 is a fragmentary elevational view of the spout of the coffee pot showing a further detail of our new design.

We claim:

The ornamental design for a coffee pot as shown.

JAMES K. MATTER.
CARLTON G. TOWNE.
